UNITED STATES PATENT OFFICE.

ALBERT STERN, OF YONKERS, AND PHILIP K. STERN, DECEASED, LATE OF NEW YORK, N. Y., BY ELIZABETH L. STERN, OF NEW YORK, N. Y., EXECUTRIX; SAID ELIZABETH L. STERN ASSIGNOR TO SAID ALBERT STERN.

SIGNALING SYSTEM.

1,144,873.

Specification of Letters Patent. Patented June 29, 1915.

Application filed April 22, 1914. Serial No. 838,766.

To all whom it may concern:

Be it known that we, ALBERT STERN and ELIZABETH L. STERN, respectively a subject of the King of Great Britain and a citizen of the United States, and residents of the city of Yonkers, in the county of Westchester, and of the city of New York, borough of Manhattan, in the county of New York, and both of the State of New York, 10 the said ELIZABETH L. STERN, executrix of the estate of PHILIP K. STERN, deceased, late a citizen of the United States, and late a resident of the city of New York, borough of Manhattan, in the city and State of New York, who did during his lifetime, 15 jointly with said ALBERT STERN, invent a new and Improved Signaling System, do declare the following to be a full, clear, and exact description of the same.

20 This invention relates to signaling systems, and has reference more particularly to signaling systems for vehicles.

An object thereof is to provide a signaling system which is inexpensive, simple, compact, strong, durable, and efficient, whereby the anticipated movements of the vehicle are annunciated by the party controlling the course of the vehicle, thus promoting the safety of the vehicle against accidental 25 collision in traffic, therefore making traffic safer.

A further object of the invention is to provide a signaling system whereby illuminated or audible signals or both together 30 can be actuated simultaneously with the indicator of the vehicle's movements.

A still further object of the invention is to provide a signaling system wherein electric energy is used for the operation of the 35 system and wherein there is a closed circuit only when a signal is transmitted.

These objects are obtained by the diagrammatic representation of a mechanism illustrated in the accompanying drawings forming 40 part of this specification, in which similar characters of reference indicate corresponding parts in all the views and wherein—

Figure 1 is a diagrammatic view of the 45 signaling system; Fig. 2 is an enlarged view of the transmitting mechanism; and

Fig. 3 is an end view of the member carrying the signs.

Referring to the drawings, 1 represents the transmitting mechanism or controller, 55 which is preferably located on the means for steering the vehicle, or in a place easily accessible therefrom; and 2 represents the annunciating apparatus adapted to be situated in a conspicuous position on the front 60 or rear of the vehicle or both. The annunciator is provided with a permutable sign adapted to be actuated through the medium of the transmitting mechanism by an electric source 3, such, for example, as a second- 65 ary battery.

The transmitting mechanism 1, which is preferably cylindrical in shape, is provided in the axis thereof with a rotatably mounted axle *c* which bears in the ends *A* of the 70 casing. Secured to said axle *c* within the casing is a metallic disk *b* which carries a ratchet wheel *a* of insulating material. The teeth *e* of the ratchet wheel are provided with metallic tips *f*, preferably formed of a 75 pin driven into the base *b*. These metallic tips are adapted to contact with a brush *g* when the axle is rotated in the direction shown by the arrow by means of the handle *d* provided on the axle *c* outside of the casing of the transmitter. The brush *g* is carried by a spring-pressed pawl *h* formed of insulating material and mounted to swing on a pivot *i* secured to one of the ends *A* of the casing of the transmitter. The said 80 pawl *h* is preferably formed of a coil spring mounted on a stud *j* provided on the pawl *h*, with one end *k* abutting against a pin *j'* carried by the pawl *h* and forming a stop for the said end *k* of the brush *g*. The 85 other end *g'* of the brush is free and is adapted to contact with the tips *f* when the ratchet is rotated by means of the handle *d*. The pawl *h* is maintained in its normal position by a spring *i'*, one end *i''* of which 90 bears against the pin *j'* and the other end of which is engaged in a slot provided in the pivot *i*. The reason for forming the brush *j* of a coil spring is to prolong the contact between the end *g'* of the brush with the 95 tips *f*.

The annunciator mechanism 2 is formed

of a casing or support *n*, the drawing showing the end of the casing removed to better illustrate the details of construction of the device, the front *n'* of the casing is provided with an arcuated window *x*, shown in dotted line, behind a disk *p*, forming the permutable sign. The said disk *p* is mounted to rotate on a shaft *o* which is carried by the front and rear of the casing *n*. The disk *p* is provided with a series of symmetrically disposed arcuated apertures *P*, each adapted to register with the arcuated window *x*. A translucent sign *P'* is provided in each of said apertures *P*, which sign is preferably formed of celluloid or any other similar and suitable material. One of said translucent members *P'* is blank. The succeeding members bear the words "Left", "Right" and "Stop". The word "Left" is made of white letters on a green background; the word "Right", of black letters on an orange background; and the word "Stop", of white letters on a red background. The unlettered member is entirely white.

A ratchet wheel *C* is carried axially by the disk *p* and has the same number of teeth thereon as the ratchet *a* in the controller, and twice the number of teeth as there are arcuated apertures or signs carried by the disk *p*. Engaging the teeth of the ratchet *C* is a spring-pressed pawl *s* which is pivotally mounted on an arm *r*, which in turn is mounted to turn freely on the shaft *o*. The back-lash of said ratchet *C* is checked by a spring-pressed pawl *N* mounted on a pin *N'* carried by the rear end of the casing *n*.

Mounted in the casing *n* adjacent the disk *p* is an electro-magnet *m*, the armature *v* of which is connected to a pitman *w* by a lug *w'* forming preferably an integral part of the end of the pitman. The other end of said pitman is provided with an adjustable, terminal lock-nut *z*, against which thrusts one end of a compression spring *a'*, the other end of said spring abutting against an extension *b'* forming an integral part of the rear of the casing *n*. The said extension *b'* forms one bearing for the pitman *w*, the other bearing being formed of a second extension *c'* from the rear of the casing *n* provided adjacent the armature *v*. The said pitman is provided centrally with a slotted crosshead *y*, the slot *t'* of which engages a pin *t* carried by the arm *r*.

The current from the source 3, by which the electromagnet *m* is energized, passes through a part of the electric conduit 11 from where it is branched off by a conduit 14, through a switch 15 to the brush *g*, which brush is insulated from the casing of the transmitter. The current continues to flow from the brush *g* through the tips when the same are in contact with the brush, through the disk *b*, through the axle *c*, which is in-

sulated from the casing 1, conduit 20, to the electro-magnet, then through the ground and back to the source 3. When the handle *d* of the transmitter is rotated, the tips *f*, carried by the teeth *e* of the ratchet *a*, come successively in contact with the brush *g*, and thus the circuit is successively opened and closed. After each contact of a tip *f* with the brush *g*, the magnet *m* is energized, attracting the armature *v*, which will compress the spring *a'* and cause the arm *r* to move on the axis due to the engagement of the pin *t* with the slot *t'* of the pitman *w*, thus bringing the pawl *s* carried by the arm to the next tooth of the ratchet wheel *C* carried by the disk *p*. When the contact between the brush *g* and tips *f* is broken, the strain on the spring *a'* is released, and the same forces the pitman, with the armature *v* to its normal position, causing the ratchet *C* and the disk *p* to rotate through one tooth. Therefore, it will be seen that a predetermined angular displacement of the handle *d* will produce an equivalent angular displacement of the disk *p*.

The end *A* of the casing of the transmitter, where the handle *d* is located, is indexed adjacent the periphery by characters corresponding to the words "Stop," "Right," "Left" and the blank provided in the disk *p*; and the angular distance between these characters is the same as the angular distance between the words "Stop," "Right," "Left" and the blank in the disk *p*. Said characters are indicated in Figs. 1 and 2 by letters *S*, *R*, *L* and *O*. To bring the sign "Left" in register with the window *x*, the handle *d* must be rotated to the point *L* (see Figs. 1 and 2), that is, the circuit between the source and the electro-magnet will be broken and established six times, thus compressing the spring *a'* six times successively, which will rotate the disk through six teeth of the ratchet *C*, bringing the sign "Left" in register with the window *x*. If it is desired to next bring the sign "Stop" in alignment with the window *x*, the handle *d* would be rotated from the point *L* to the point *S*, thus it is necessary to make four more contacts, rotating the disk *p* through four teeth. It will be noted that the handle *d* rotates always in the same direction; and any of the signs may quickly and easily be brought into register with the window *x* by simply placing the handle *d* in alignment with the corresponding index or character. The reason for first energizing the spring *a'*, which then rotates the disk, is to reduce the hammering effect of the electro-magnet when the same is used directly as means for moving the disk *p*.

In addition to the visual, legible annunciator involved in rotating the handle *d*, an audible alarm is provided, which can be positioned in any suitable place and can be in any desired form. As shown in the draw-

ings, it is a horn, which can be cut in by the movement of the switch 15, so that the current from the source, instead of flowing through the transmitter from the conduit 11, through the branch 14, will flow through the branch 17, through the horn 8, through the switch 15, etc. Therefore, when the annunciator is operated by the transmitter, the horn will be intermittently energized due to the make and break in the circuit.

To make the annunciator visible in the night, the same is provided in the casing *n* with an electric lamp 21, which is positioned behind the disk *p* so as to throw light 15 through the translucent member coming in register with the window *x*. The disk *p* carries a stud *d'* which is adapted to come in contact with the resilient members *g''*. Said members are so positioned within the casing 20 *n* that the stud *d'* comes in contact with them when a corresponding lettered sign registers with the window *x*. The members *g''* are connected to the conduit 11 by means of branch conduits 11', each provided with a 25 switch *h'*, shown closed in dotted position on each of said branches.

When the disk *p* is in normal position, *i.e.*, the unlettered blank *P'* is in register with the window *x*, there is no necessity for the lamp 21 to be lighted; but when any of the lettered blanks *P'* is brought into register with the window *x*, the lamp 21 receives current through the contact of the stud *d'* with any of the members *g''*. The current from 30 the source 3 coming to the member *g''*, passes through the member *g''*, through the disk, through the shaft *o*, from the shaft through the lamp 21 and then to the ground, from the ground back to the source. Thus, 35 the lamp 21 is energized whenever the stud *d'* contacts with any of the members *g''* and, therefore, whenever there is a lettered blank *P'* in register with the window *x*. It will be noted that when energy is supplied to the 40 electro-magnet, there is no supply of energy to the lamp unless the switches *h'* are closed and the stud *d'* contacts with the member *g''*. When the stud *d'* is in contact with any 45 of the members *g''*, the supply from the electro-magnet has been cut off. The switches *h'*, which are provided on the branches 11', permit the cutting out of the light during 50 the day service of the apparatus, and, thus, the energy for the operation of the system is 55 used only when the same is operated.

In addition to the readable, colored signs, the system is provided with lamps 4, 5 and 7, each connected to the corresponding branch 11', and where, by the closing of the 60 switches *h'*, the current from the source flows through the members *g''* and is made to pass through the lamps positioned in each of the corresponding branches. The lamp 4 has the same color as the sign provided with

the word "Stop," because the stud *d'* will 65 come in contact with its corresponding member *g''* when said sign is in register with the window *x*. Similarly, lamp 5 has the color of the sign provided with the word "Right"; and lamp 7, that of the sign having the word "Left." The provision of 70 these lamps, which may be positioned in any suitable place on the vehicle, will further help to indicate the anticipated movements of the vehicle. By means of the 75 switches *h'*, the indicator can be used with or without said lamps, *i.e.*, the same can be operated when the annunciator is operated, or the annunciator may be operated without the lamps 4, 5 and 7 being operable. 80 The lamp 6 provided in one of the branches 11' is simply intended as an indicator on the dashboard to show whether or not the system is operating.

Having thus described the invention, we 85 claim as new and desire to secure by Letters Patent:

1. In a signaling system, an annunciator comprising a casing having an opening, a member carrying differently colored signs 90 mounted to rotate in said casing, means for operating said member whereby the differently colored signs can be brought in register with the opening in the casing, a lamp in said casing for illuminating the signs, a 95 lamp for each of the colored signs colored similarly to the corresponding sign, a circuit for all of said lamps, and means carried by said member carrying the signs for controlling the circuit, whereby when one of said 100 colored signs is in register with the opening of the casing, the lamp in the casing and the lamp colored to correspond to the sign registering with the opening are illuminated.

2. In a signaling system, an annunciator 105 comprising a casing having an opening, a member carrying differently colored signs mounted to rotate in said casing, means for operating said member whereby any of the colored signs can be brought in register with 110 the opening of the casing, a lamp in said casing, lamps colored similarly to the signs, contacting points in said casing, each in connection with a colored lamp, an electric circuit for all of said lamps, and a member 115 carried by said sign-carrying member adapted to complete the circuit by engaging the contact of a lamp colored similarly to the sign when the same is in register with the opening of the casing; the lamp in the casing 120 being so related to said member completing the circuit that the same is always in the circuit when any of the colored lamps is illuminated.

3. In a signaling system, an annunciator 125 having a member mounted to rotate, said member adapted to carry signs of different color, a ratchet associated with said mem-

ber, a pawl engaging said ratchet and preventing the retracting movement thereof, an arm mounted to swing in the axis of the ratchet, a spring-actuated pawl carried by said arm and engaging said ratchet, a pin on said arm, a slide having a slot engaging said pin, a spring tending to maintain said slide in a predetermined position, and an electro-magnetic arrangement associated with said slide whereby the same can be moved and whereby said arm is caused to swing, the return movement of said slide being obtained by the spring, whereby the ratchet is caused to turn substantially as and for the purpose set forth.

In testimony whereof I have signed my

name to this specification in the presence of two subscribing witnesses.
